UNITED STATES PATENT OFFICE.

WILHELM B. BRONANDER, OF MONTCLAIR, NEW JERSEY.

DIE-PRESS.

1,397,358.

Specification of Letters Patent. Patented Nov. 15, 1921.

Application filed March 4, 1920. Serial No. 363,130.

To all whom it may concern:

Be it known that I, WILHELM B. BRONANDER, a citizen of the United States, and a resident of Montclair, Essex county, and State of New Jersey, have invented certain new and useful Improvements in a Die-Press, of which the following is a specification.

My present invention relates to die presses of the type such as are employed in the pressing of phonograph records.

These presses must be closed under heavy pressure and this heavy pressure, to get the best results, should be applied somewhat gradually. This slow application of power usually results in cutting down the speed and hence the output of the machine.

One of the principal objects of my invention is to combine in the one machine both the advantages of quick operation and the slow powerful closing pressure.

These objects I have attained by means of a special "double toggle" construction which operates first to bring the coöperating members of the press together with a relatively quick motion and to then apply a final heavy closing force.

Other special objects and features of the invention will appear in the course of the following specification.

In the drawings accompanying and forming a part of this specification I have illustrated the invention embodied in one of its practical and preferred forms, but would have it understood that the same may be modified in various respects without departure from the true spirit and scope of the invention as defined in the appended claims.

Figure 1 in said drawings is an end view of the press with the parts in the final closed relation, the driving shaft being shown in section as taken on substantially the plane of line 1-1 of Fig. 2.

Fig. 2 is a view of the front or left-hand side of the press shown in Fig. 1.

Figs. 3 and 4 are vertical sectional views as taken on substantially the plane of line 3-3 of Fig. 2 and showing the press elements in the partly closed and in the fully open positions respectively.

Fig. 5 is an enlarged sectional view of the timing mechanism, as taken on substantially the plane of line 5-5 of Fig. 6.

Fig. 6 is a sectional view of the same as taken on substantially the plane of line 6-6 of Fig. 5.

In the illustration 10 designates the base

or bed of the press and 11 the movable head or gate coöperating therewith, the base being shown in this instance as supported in inverted relation at the top of the posts or columns 12 on which the head is guided by means of the sleeves 13. The head is shown as cushioned by means of suitable springs 14, which, as indicated more clearly in Fig. 4, may be connected at opposite ends at 15, 16 and 17 with the two press parts so as to form resilient stops limiting the opening movement of the press.

The press illustrated is designed particularly for pressing phonograph records and the same is accordingly provided with co-operating matrix or die members 17 and 18 between which the record is formed.

Special means for heating and cooling these die members is disclosed in the illustration in the form of a steam or heating fluid supply conduit 19 and a water or cooling fluid conduit 20 which are controlled by a two-way valve 21 having an operating handle 22 which is actuated by the two spaced stops 23 and 24 carried by the press head, the fluid controlled by said valve passing through the piping 25 and the flexible tubing 26 and 27 to the upper and lower die members respectively.

The arrangement of the valve actuating mechanism is such that on the opening or lowering movement of the press head, the upper trip 23 will engage the valve handle and rock the same from the position shown in Fig. 3 to the position shown in Fig. 4, so as to turn on the flow of steam or heating fluid. Hence, as the press is opened, the heating fluid is automatically admitted to the dies, so that when the press is ready to close the dies are hot and therefore in condition to operate on the material being molded. As the press closes, however, the lower stop 24 engages the valve handle and swings the same to the position shown in Fig. 3, so as to shut off the steam and to turn on the water or cooling fluid. Hence, as the press is closed, the cooling fluid is automatically admitted to the dies, so as to cause the material to quickly set.

The mechanism for quickly closing the press and for applying the final heavy pressure comprises a toggle made up of the two levers 30 and 31 pivoted together at 32, the lower of these levers being pivoted or fulcrumed at 33 in the base or frame 34 of the machine and the upper lever 31 being piv-

oted at 35 to the lower end of a link 36 which is pivoted at 37 to the movable press head. This upper link or lever 36 is actuated as a toggle lever by means of a rod 38 pivoted to 5 the lever 36 at a point 39 between and to one side of the pivotal centers 35 and 37 and which rod is longitudinally slotted at its lower end at 40 to receive a crank pin 41 carried by the shaft 42. The shaft 42 also 10 carries a cam 43 for engagement with a roll 44 on the intermediate toggle pivot 32.

The shaft rotates in the direction of the arrow indicated in Fig. 4 from which it will be seen that as the crank pin reaches the 15 upper end of the slot in the connecting rod 38, the same will be operated as a push rod to swing the upper lever 36 around the center 35 as a fulcrum, the first air of toggle levers 30, 31 being then under tension and 20 standing in substantially straightened condition. As this movement continues the upper lever 36 snaps over into engagement with a stop 45 (Fig. 3). The movement described results in a quick closing action 25 of the press and as the press parts approach the closed position, the cam 43 comes into operation and engages the roll 44 (Fig. 3) to straighten or partially straighten the lower toggle 30—31, as indicated in Fig. 1, 30 thereby exerting a final powerful closing force.

In the opening of the press the reverse actions take place, the cam first turning away from the toggle pivot so as to release 35 the final squeezing pressure and the rod 38 being operated as a pull link, when the crank pin engages the lower end of the slot therein, to break the upper toggle and bring the parts from the position illustrated in Fig. 1 40 to the position indicated in Fig. 4.

The three toggle levers, it will be seen, thus constitute in effect a compound or double-jointed toggle, one joint of which is operated to effect a relatively rapid movement of the press parts and the other joint of which is subsequently operated to effect a slow powerful closing action of the press parts.

Another feature of the invention is the 50 provision of timing mechanism for holding the press closed a predetermined period of time. In the present disclosure this timing mechanism is constructed as follows.

In Fig. 2 I have shown a drive shaft made 55 up of two sections 50 and 51 which may be coupled together by a clutch 52, power being applied to one of such shaft sections as by means of the balance wheel indicated at 53. When the machine is in operation the drive 60 section 50 of the shaft will operate continuously and the driven section 51 will be operated only when the clutch 52 is in engagement. The driven shaft section 51 carries a pinion 54 in mesh with an internal gear 55 65 on the cam and crank shaft 42. This gear

wheel 55 also serves as a balance wheel and in addition carries a cam track 56 having at diametrically opposite points the cam protuberances 57 and 58. These cam elements 57 and 58 engage the roller 59 of a clutch 70 controlling rod 60 which is slidably mounted in the base and carries at its inner end a pivoted bell crank 61 for engagement with the lower end of the pivoted clutch shifting lever 62. In the position of the parts indicated in Fig. 2, with the press fully closed the cam 58 has forced inward the slide 60 and this through the bell crank connection described has operated the clutch shifting lever to uncouple the clutch so that under 80 such conditions the machine is tripped with the co-operating press parts in closed relation.

Connected with the movable press head is a link 65 which engages at its lower end the angle arm 66 of a pivotally supported pawl 67 and which pawl is disposed when thus actuated by the movable press head to engage the teeth of a ratchet wheel 68 rotatably supported on the driving shaft section 90 50. This ratchet is shown in Figs. 5 and 6 as fixed on a sleeve 69 which is rotatably engaged on the shaft section 50 and rotatably engaged on this sleeve is a second sleeve or bushing 70 carrying gear teeth 71 engaged 95 by pinions 72. Affixed to or forming a part of the pinions 72 are the pinions 73 meshing with the gear teeth 74 carried by the ratchet sleeve 69. The pinions 72 and 73 are journaled on studs 75 supported on a disk or hub 76 keyed or otherwise fixedly secured on the driving shaft section.

From the structure thus far described it will be apparent that when the press is closed (Fig. 1), the pawl will be thrown 105 into engagement with the ratchet and the ratchet will be thereby held against rotation while the driving section of the shaft continues to rotate. In such continued rotation of the shaft the pinions 73 will be carried about the ratchet gear 74 and will be rotated thereby. The pinions 72 forming a part of the pinions 73 are thus driven and their motion is communicated to the gear 71 on the loose sleeve member 70, consequently, when the ratchet is caught by the pawl, the sleeve member 70 will be rotated, but in a direction the reverse of the direction of rotation of the shaft section 50. The relative movements of the shaft 50 and the 110 sleeve element 70 are indicated by the reversely pointed arrows in Fig. 5. Also, the gearing described is preferably of the speed reduction type so that not only will the sleeve 70 be rotated in the reverse direction, 115 but will be rotated at slower speed than the shaft section 50.

The reversely rotating sleeve 70 carries a trip shown in the form of a beveled cam 80 which is adjustably secured circumferen- 120

tially about the sleeve by means of the bolts 81 having heads engaging in the undercut circumferential groove 82. The trip cam 80, as shown in Fig. 2, is arranged to engage 5 a cam shoulder 83 on a slide rod 84 which is connected with the lower arm 85 of the bell crank lever 61. Consequently, when the trip cam 80 in the course of its reverse rotation, strikes the cam shoulder 83 the slide rod 84 10 will be shifted inward and the bell crank 61 will be tripped to release its hold on the clutch shifting lever 62 and when this happens the clutch spring 86 will again throw the clutch in engagement, coupling the two 15 shaft sections together and causing the crank shaft to be operated to trip the toggle and open the press.

By reason of the adjustability of the trip cam 80, the period during which the press 20 is held closed may be varied at will.

When the parts are tripped as described, to open the press after the elapsed period of time predetermined upon, the timing gearing is restored to its original relation 25 with the stop 93 on the trip gear (Figs. 1 and 5) in engagement with a stop 92 provided on the base of the machine. This restoration is due partly to the friction of the sleeves on the shaft which causes the 30 trip sleeve to rotate with the shaft until the stop 93 engages stop 92, but may be assisted and made quicker in operation by the provision of a restoring spring which I have indicated at 90 as connected between the 35 stop 92 on the base and the trip sleeve, the inner end of such coil spring being shown as connected with the trip sleeve at 91.

This spring, it will be evident, is tensioned by the relative rotation of the 40 ratchet sleeve and trip sleeve when the ratchet is caught by the pawl and exerts such tension, when the pawl releases the ratchet, to rotate the trip sleeve back to its former position with the shoulder 93 in engagement with the stop 92, which stops thus 45 constitute coöperating abutments to fix the initial position of the trip.

It will be clear from the description thus far that by the mechanism described the 50 press is brought with a relatively rapid motion to substantially the closed position, a powerful squeezing pressure is then applied to fully close the press and that the press is then held closed for a predetermined period, after which it is opened with a relatively quick motion. When this cycle of operations has been completed, the press is stopped by cam 57 and remains in this open condition until it is again started by some 55 act on the part of the operator. In the machine herein disclosed, the press is started by a foot pedal 100 which is shown in Fig. 2 as connected by a link or pull cord 101 with the spring-pressed bell crank lever 61. 60 It will be clear from this view that when

said pedal is depressed the bell crank will be tripped from engagement with the clutch shifting lever 62 and the clutch will be thereby dropped into engagement so as to start the machine.

70 While I have shown timing mechanism which is operated only for the purpose of holding the press closed through a predetermined period of time, it will be apparent that this mechanism might be duplicated 75 for the purpose of holding the press open and for starting the same again after the lapse of predetermined time.

This and other modifications and changes will come within the scope of the present 80 invention as will be clear from the claims appended.

What I claim is:

1. The combination with a press having a movable press element, of a double-jointed 85 toggle supported at one end and connected with the movable press element at its opposite end, means for operating one of the joints of said toggle with a relatively quick movement and means for operating the other 90 joint of the toggle with a slower movement.

2. The combination with a press having a movable press element, of a compound toggle supported at one end and connected with the movable press element at its opposite end, 95 means for operating one of the joints of said compound toggle through a relatively great range of movement and means for operating another joint of the toggle through a lesser range of movement.

100 3. The combination with a movable press element, of a compound toggle supported at one end and connected at the opposite end with said movable press element, means for operating one of the joints of said compound 105 toggle through a relatively great range of movement and with a relatively rapid motion and means for operating another joint of the compound toggle through a lesser range of movement and at a lesser rate of 110 speed than the first joint.

4. The combination with a movable press element, of a multiple jointed toggle supported at one end and connected at the opposite end with the movable press element, a 115 quick acting crank connected to operate one of the joints of said toggle and a slower acting cam arranged to operate another joint of said toggle.

120 5. The combination with a movable press element, of a multiple jointed toggle supported at one end and engaged with the movable press element at its opposite end, means for making and breaking one of the joints of said toggle and means for partially 125 straightening another joint of said toggle.

6. The combination with a movable press element, of a multiple jointed toggle supported at one end and connected with the movable press element at its opposite end, 130

means for making and breaking one of the joints of the toggle and means for subsequently operating on another joint of the toggle.

- 5 7. The combination with a movable press element, of a multiple jointed toggle supported at one end and connected at the opposite end with the movable press element, means for straightening one of the joints of the toggle and sequentially operating means for applying a straightening force to another joint of the toggle.
- 10 8. The combination with a movable press element, of a double-jointed toggle supported at one end and connected at the opposite end with the movable press element, means for straightening one joint of said toggle and sequentially operating means for then applying a straightening force to the second joint of the toggle.

- 15 9. The combination with a movable press element, of a double-jointed toggle comprising end levers and an intermediate lever, a pivotal support for one of said end levers, a pivotal connection between the other of said end levers and said movable press element, an actuating connection with one of said end levers and a connection with the joint between the opposite end lever and the

- 20 intermediate lever.
10. The combination with a movable press element, of a double-jointed toggle comprising end levers and an intermediate lever, a pivotal support for one of said end levers, a pivotal connection between the other said end levers and said movable press element and separate differently timed actuating means for operating the two joints between the end levers and the intermediate lever.

- 40 11. The combination with a movable press element, of a double-jointed toggle comprising three pivotally connected levers, a pivotal support for one of the end levers of said toggle, a pivotal connection between the opposite end lever and the movable press element, an operating connection engaged with said last mentioned toggle lever and actuating means for operating the joint between the other end toggle lever and the intermediate toggle lever.

- 45 12. The combination with a movable press element, of a double-jointed toggle lever comprising pivotally connected levers, a pivotal support for one of the end toggle levers, a pivotal connection between the other opposite end toggle lever and the movable press element, means for operating the joint between one of the end toggle levers and the intermediate toggle lever, means for limiting the straightening movement at said joint and means for operating the joint between the other end toggle lever and the intermediate lever.

- 50 13. The combination with a movable press element, of a double-jointed toggle comprising

ing three pivotally connected levers, a pivotal support for one of the end levers of the toggle, a pivotal connection between the opposite end lever and the movable press element and means for sequentially operating the two joints between the end levers and the intermediate lever.

70 14. The combination with a movable press element, of a double-jointed toggle comprising three pivotally connected levers, a pivotal support for one of the end levers of the toggle, a pivotal connection between the opposite end lever and the movable press element, an operating connection engaged with one of the end levers at a point to one side of a line between the pivots at the opposite ends of said lever and means for operating the joint between the opposite end lever and the intermediate lever.

75 15. The combination with a movable press element, of a double-jointed toggle comprising three pivotally connected levers, a pivotal support for one of the end levers of the toggle, a pivotal connection between the opposite end lever and the movable press element, an operating connection engaged with one of the end levers at a point to one side of a line between the pivots at the opposite ends of said lever and means for operating the joint between the opposite end lever and the intermediate lever including a cam and an abutment member at said latter joint and engaged by said cam.

80 16. The combination with a movable press element, of a double-jointed toggle comprising three pivotally connected levers, a pivotal support for one of the end levers, a pivotal connection between the opposite end lever and the movable press element, a push and pull link connection with one of the end toggle levers and means for operating the joint between the opposite end toggle lever and the intermediate lever.

85 17. The combination with a movable press element, of a double-jointed toggle comprising three pivotally connected levers, a pivotal support for one of the end levers of said toggle, a pivotal connection between the opposite end lever and the movable press element, means for operating the joint between one of the end levers and the intermediate lever, a roll at the joint between the opposite end lever and the intermediate lever and an operating cam engaging said roll.

90 18. The combination with a movable press element, of a double-jointed toggle comprising three pivotally connected levers, a pivotal support for one of the end levers of the toggle, a pivotal connection between the opposite end lever and the movable press element, a crank, a link engaged between said crank and one of the toggle levers and having a lost motion connection with one of said parts and means for controlling the operation of the other toggle levers.

19. The combination with a movable press element, of a double-jointed toggle comprising three pivotally connected levers, a pivotal support for one of the end levers of the 5 toggle, a pivotal connection between the opposite end lever and the movable press element, a crank pivoted to one of the toggle levers and having a lost motion connection with the crank and means for operating the 10 other toggle levers.
20. The combination with a movable press element, of a double-jointed toggle comprising three pivotally connected levers, a pivotal support for one of the end levers of the 15 toggle, a pivotal connection between the opposite end lever and the movable press element, a crank pivoted to one of the toggle levers and having a lost motion connection with the crank and means for operating the 20 other toggle levers including a cam rotating with the crank and arranged to engage a member carried by said other toggle levers.
21. The combination with a movable press element, of a compound toggle comprising 25 three pivotally connected levers, a pivotal support for one of the end levers of said toggle, a pivotal connection between the opposite end lever and the movable press element, means connected with said end lever for 30 swinging the same about its pivotal connection with the intermediate lever and said intermediate lever and a pivotally supported end lever forming a swinging fulcrum link for the end lever which is connected with the 35 movable press element.
22. The combination with a movable press element, of a compound toggle comprising three pivotally connected levers, a pivotal support for one of the end levers of said 40 toggle, a pivotal connection between the opposite end lever and the movable press element, means connected with said end lever for swinging the same about its pivotal connection with the intermediate lever and said 45 intermediate lever and a pivotally supported end lever forming a swinging fulcrum link for the end lever which is connected with the movable press element and means for controlling the joint between the intermediate lever and said pivotally supported end 50 lever.
23. The combination with a movable press element, of a compound toggle comprising 55 three pivotally connected levers, a pivotal support for one of the end levers of said toggle, a pivotal connection between the opposite end lever and the movable press element, means connected with said end lever for swinging the same about its pivotal connection with the intermediate lever and said 60 intermediate lever and a pivotally supported end lever forming a swinging fulcrum link for the end lever which is connected with the movable press element and means for controlling the joint between the intermediate 65 lever and the movable press element.
24. In combination, a press, means for opening and closing said press and timing 70 mechanism operated by and controlling said opening and closing means to maintain the press closed for a predetermined period of time.
25. In combination, a press, actuating 75 means for opening and closing said press and variable timing mechanism operated by and controlling said actuating means to maintain the press closed throughout a variably determinable period of time.
26. In combination, a press, actuating 80 means for opening and closing the press and timing mechanism operated by and controlling said actuating means to maintain the press in one condition throughout a pre- 85 determined period of time.
27. In combination, a press, actuating 90 means for opening and closing the press and variable timing mechanism operated by and controlling the actuating means and adjustable to maintain the press in one condition throughout a variably predetermined period of time.
28. In combination, a press, actuating 95 means for opening and closing said press and automatic mechanism operated by and controlling said actuating means to close the press and maintain it closed throughout a predetermined period of time and to there- 100 upon open the press and hold the same open.
29. In combination, a press, actuating means for opening and closing said press, automatic mechanism operated by and controlling said actuating means to close the press and maintain it closed throughout a 105 predetermined period of time and to there- upon open the press and hold the same open and manually controlled means for tripping said mechanism to repeat the cycle of operations described.
30. In combination, a press, actuating 110 means for closing and opening said press, power means, a clutch connection between said power means and said actuating mechanism and timing mechanism operated with the actuating mechanism and controlling said clutch.
31. In a press, actuating means for closing and opening the press including a shaft, a cam operated by movement of said shaft, 115 a drive clutch for said shaft and connections actuated by the cam for controlling said clutch.
32. In a press, actuating means for closing and opening the press, shaft sections, a 120 clutch connection between said shaft sections, drive connections from one of said shaft sections to the actuating means and clutch controlling means actuated by one of said shaft sections.

33. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet and mechanism operated by the trip and controlling the clutch.

34. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch and means for adjustably supporting the trip on the trip sleeve aforesaid.

35. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch and a spring connected with the trip sleeve for restoring said sleeve to an initial relation when the ratchet is released from the pawl.

36. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch and manually operable means for actuating the clutch.

trolling the clutch and means for controlling the clutch independently of said trip mechanism.

37. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch, a cam operated from the driven shaft section and clutch controlling means actuated by said cam.

38. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch and clutch controlling trip mechanism actuated by the driven shaft section.

39. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch and clutch controlling trip mechanism actuated by the driven shaft section and manually operable means for actuating the clutch.

40. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft

- section, gears carried by said support and meshing with the gears on the ratchet sleeve and trip sleeve, a pawl controlling by the press and arranged to engage the ratchet, mechanism operated by the trip and controlling the clutch, the press actuating means aforesaid including a shaft operated from the driven shaft section, a crank and a cam on said operated shaft and a compound toggle operated by said crank and cam.
41. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch, a pinion on the driving shaft section, a gear engaged by said pinion, a cam carried by said gear, a slide actuated by said cam and connections between said slide and the clutch.
42. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the clutch, a pinion on the driving shaft section, a gear engaged by said pinion, a cam carried by said gear, a slide actuated by said cam, connections between said slide and the clutch, a shaft operated by the gear, a crank and a cam on said shaft and a compound toggle operated by said crank and cam and forming a part of the press actuating means referred to.
43. In combination, relatively movable press elements, heating and cooling connections to said elements, valve mechanism controlling admission of heating and cooling fluid to said connections and a plurality of variously characterized means carried by one of the relatively movable press elements comprising a member for automatically shifting said valve in the opening operation of the press, and a second member for automatically shifting said valve in the closing operation of the press.
44. In combination with a press having a movable press element, heating and cooling connections to said element, a valve controlling admission of heating or cooling fluid to said connections and a plurality of variously characterized means carried by the movable press element comprising a member for automatically actuating said valve in the opening movements of the press, and a second member for actuating said valve in the closing movement of the press.
45. In combination with a movable press element, heating and cooling connections to said element, a valve for controlling admission of heating or cooling fluid to said connections and a plurality of variously characterized means reciprocated by a movable portion of the press comprising a member for automatically throwing said valve to turn on the heating fluid in the opening movement of the press, and a second member for automatically throwing said valve to turn on the cooling fluid in the closing movement of the press.
46. In combination with a movable press element, heating and cooling connections thereto, a two-way valve controlling flow of heating or cooling fluid to said connections and a plurality of variously characterized means comprising a member for operating said valve in the opening movement of the press to admit heating fluid to the movable press element and a second member independent of said first named member for operating the valve in the closing movement of the press to admit cooling fluid to the movable press element.
47. In combination with a movable press element, heating and cooling connections thereto, a two-way valve controlling flow of heating or cooling fluid to said connections and means for operating said valve in the opening movement of the press to admit heating fluid to the movable press element and for operating the valve in the closing movement of the press to admit cooling fluid to the movable press element, said means including a pair of spaced stops carried by the movable press element and arranged to operatively engage a part of the valve mechanism.
48. In a press, driving and driven shaft sections, press actuating means operated by the driven shaft section, a clutch connection between said shaft sections, a sleeve rotatably engaged on the driving shaft section and provided with a gear and with a ratchet, a sleeve rotatably engaged on said ratchet sleeve and provided with a gear and with a trip, a support fixed on the driving shaft section, gears carried by said support and meshing with the gears on the ratchet sleeve and trip sleeve, a pawl controlled by the press and arranged to engage the ratchet, mechanism operated by the trip and controlling the

clutch and means for returning the trip to a predetermined position when the ratchet is released by the pawl.

49. In a press, driving and driven shaft sections, press actuating means operated by the driven shaft section, a clutch connection between said shaft sections, a sleeve rotatably engaged on the driving shaft section and provided with a gear and with a ratchet, 10 a sleeve rotatably engaged on said ratchet sleeve and provided with a gear and with a trip, a support fixed on the driving shaft section, gears carried by said support and meshing with the gears on the ratchet sleeve

and trip sleeve, a pawl controlled by the 15 press and arranged to engage the ratchet, mechanism operated by the trip and controlling the clutch, means for returning the trip to a predetermined position when the ratchet is released by the pawl, including a relatively 20 stationary stop, a coöoperating stop on the trip sleeve and a spring acting on the trip sleeve to rotate the same in a direction to bring the stop carried thereby into engagement with the relatively stationary stop. 25

In witness whereof, I have hereunto set my hand this 1st day of March, 1920.

WILHELM B. BRONANDER.
